FRANK NARDONE, OF PHILADELPHIA, PENNSYLVANIA.

ACCORDION.

Application filed March 28, 1927. Serial No. 178,826.

My invention relates to musical instruments having rows of reeds for the production of the musical notes and more particularly to accordions.

In playing an accordion, advantageous effects may be produced by changing the tonal harmony of the instrument during certain stages of the composition being played, and the principal object of my invention is to provide means whereby such changes may be easily made by the player.

Another object of my invention is to provide means, for changing the tonal harmony of an accordion, which may be mounted in the interior of the instrument without in any way interfering with its moving parts.

Still another object of my invention is to so design such mechanism that the same movement of the operating lever will both close and open certain valves.

These objects, and other, advantageous ends which will be described hereinafter, I attain in the following manner, reference being had to the accompanying drawings in which

Figure 1 is a front view of a portion of an accordion embodying a preferred form of my invention, certain parts being broken away in order to illustrate certain mechanism.

Figure 2 is a transverse sectional view of the main body part of the accordion, taken substantially on line 2—2 of Figure 1, with a portion of the keyboard and portions of the wind cells broken away.

Figure 3 is a bottom plan view of the wind cell chamber in the main body part, looking from the bottom of Figure 2; the wind cells having been omitted in order to illustrate the apertures communicating with the wind cells.

Figure 4 is a top plan view of a bank of wind cells, a certain portion being broken away in order to show a valve slide mounted therein.

Figure 5 is a plan view of the valve slide shown mounted in the bank of wind cells in Figure 4, and

Figure 6 an enlarged end view of the bank of wind cells shown in Figure 4.

Referring now more in detail to the drawings, the instrument consists of a main body part 10, a secondary body part 11, and a bellows 12 connecting body parts 11 and 12. Main body part 10 is provided with a piano type keyboard having white keys 13 and

black keys 14 while part 11 is provided with a plurality of small keys 15. A plurality of wind cells 16 are arranged in rows in body part 10 and are each provided with two reeds 17 disposed over apertures 18 formed in the side of the wind cell. One end of one reed is secured to the outside of the wind cell wall immediately above one aperture 18 and the other reed is secured to the inside of the wind cell wall above the other aperture 18. The depending portions of each reed 17 conforms in shape and size to aperture 18 and is adapted to vibrate therein. Immediately opposite each end 17, a piece of leather 19 is secured to the wind cell wall and is of sufficient size to cover aperture 18 and prevent air from passing therethrough from the side on which the leather is placed. When air is forced into a wind cell 16 through an aperture 20 formed in its top, the leather 19 on the inside of the cell will prevent the air from escaping through its aperture 18 while the one on the outside will blow away from its aperture and allow the air to escape therethrough and vibrate the reed. When air passes through the cell in the opposite direction, the leather 19 on the outside of the cell will close its aperture 18 while the leather on the inside of the cell will allow its reed to vibrate.

Wind cells 16 are arranged in pairs and a valve 21 is adapted to open and close both apertures 20 leading therefrom. Valves 21 are secured to their respective keys by means of rods 22 as shown in Figure 2. Keys 13 and 14 are hinged on a rod 23 and normally held in their upper position by means of a bent spring 24 so that, in order to depress the key and raise valve 21 away from apertures 20, it is necessary to compress spring 24.

In the accompanying drawings, the instrument is shown as having four double rows of banks or wind cells, the first and third banks having a row of round apertures 20 and a row of square apertures 20^a while the second and fourth banks of wind cells are provided entirely with round apertures. Extending bellows 12 will cause air to rush into the instrument through a perforated plate 25 which covers the valves 21 and the tops of the wind cells. With the exception of the manner of hinging keys 13 and 14, the above brief description covers a conventional type of accordion and, as its parts and mode of operation are well known, it will not be described

further than is necessary for a thorough understanding of my invention.

The top of each bank of wind cells 16 is preferably composed of a single plate 26 provided with apertures 20 which communicate with the interior of the wind cells. In carrying my invention into effect, I form a slot 27 longitudinally in plate 26 and insert therein a valve slide 28 which has apertures corresponding to the apertures 20^a in plate 26 and spaces 29 between each two apertures which is more than equal to the width of an aperture. It is evident that by moving valve slide 28 until the apertures therein are in alignment with apertures 20^a, all the wind cells in this bank may function in a normal manner while, if valve slide 28 is moved longitudinally of plate 26 until the holes therein are totally out of registry with holes 20^a only one row of cells in this bank may function. By cutting off one row of cells in certain banks, pleasing tonal effects are produced.

In order that the several valve slides 28 may be moved in unison, I provide a shaft 30 journaled in bearings 31 secured to one end of body part 10 and having arms 32 fixed therein and engaging holes 33 in the ends of valve slides 28. In the drawings, I have shown the instrument as provided with two valve slides 28, but it will be readily understood that an instrument may be provided with any number. An arm 34 has one end rigidly connected to shaft 30 and its other end pivotally connected in one end of a connecting rod 35. The other end of connecting rod 35 is pivotally connected to a pin fixed in a pinion 36 between its center and periphery, so that as pinion 36 rotates, connecting rod 35 will be reciprocated and consequently reciprocate arms 32 and valve slides 28.

In order to rotate pinion 36, I provide a gear 37 rotatably mounted adjacent pinion 36 and meshing therewith. Four pins 38 extend from one face of gear 37 at equal intervals intermediate the center and its periphery. A plunger 39 is slidably mounted in a bearing 40, secured to the end of body part 10, and terminates in a button 41 adapted to be pressed by the operator for actuating valve slides 28. Plunger 39 is normally held in its outermost position by a spring 42, having its ends secured to the plunger and body part 10, and a plunger head 43 is pivotally mounted on its other end and guided through a bracket 44 fixed to body part 10. Plunger head 43 is provided with a projection 45 adapted to engage a pin 38 when button 41 is pressed inwardly and cause gear 37 to rotate one quarter turn, at which time another pin 38 will come in contact with a second projection 46 and prevent gear 37 from rotating more than one quarter turn.

The movement of plunger 39 in either direction is further regulated by a pin 47 ex-

tending through a slot 48 formed in bearing 40 and a pawl 49, pressed by a spring 50, engages the teeth of gear 37 and prevents same from rotating in the wrong direction. In order to assure the turning of gear 37 a full quarter turn, I provide a spring 51 held in engagement with the two upper pins 38 by being connected to a pin 52 and abutting a stop 53, as plainly shown in Figure 1. If button 41 is pressed inwardly for less than its full stroke, pawl 49 will prevent gear 37 from turning in the opposite direction while spring 51 will bear against pins 38 and cause the gear to turn to its correct position.

From the foregoing it will be evident that depressing button 41 will move valve slides 28 so as to close openings 20^a; by pressing button 41 a second time, gear 37 will be rotated a quarter turn and valve slide 28 will be moved to uncover openings 20^a, and that subsequent movements of button 41 will alternately cover and uncover these apertures. In this manner the player of the instrument merely presses button 41 to obtain a change in tonal effect and does not have to remember whether to move the operating lever in one direction or the other but merely presses the button in the same direction each time. It will be further noted that, with the exception of button 41, the operating mechanism is entirely concealed, that it in no way interferes with the working parts of the accordion, and that it is so simply designed as not to be liable to get out of order. Further, an accordion made in accordance with my invention has enabled the player to produce tonal effects heretofore unobtainable.

In a conventional accordion having a piano keyboard, each key is usually hinged at a point under the inner end of the visible part of the key and, when the instrument is being played in sharps and flats, the player's fingers come so close to the pivotal point that considerable pressure is required to depress the keys. To overcome this feature, I form a key chamber at one side of the wind cell chamber, which is separated therefrom by an angular partition 54, and secure rod 23, to which the keys are hinged, near the inner end of this chamber. This arrangement allows the keys to be easily depressed even when the player's fingers are close to the back of the keyboard.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the appended claims.

I claim:

1. In an accordion having rows of wind cells, openings in the wind cells, valves for

1. closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger adapted to engage the pins and cause the gear to make a partial revolution, and a bearing for holding the plunger in alignment. 70
2. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger adapted to engage the pins and cause the gear to make a partial revolution, and a bearing for holding the plunger in alignment. 75
3. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger adapted to engage the pins and cause the gear to make a partial revolution, and a bearing for holding the plunger in alignment. 80
4. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger adapted to engage the pins and cause the gear to make a partial revolution, and a bearing for holding the plunger in alignment. 85
5. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger head adapted to engage the pins and cause the gear to make a partial revolution, and a plunger hinged to the plunger head. 90
6. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger head adapted to engage the pins and cause the gear to make a partial revolution, and a plunger hinged to the plunger head. 95
7. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger head adapted to engage the pins and cause the gear to make a partial revolution, and a plunger hinged to the plunger head. 100
8. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger head adapted to engage the pins and cause the gear to make a partial revolution, and a plunger hinged to the plunger head. 105
9. In an accordion having rows of wind cells, openings in the wind cells, valves for closing the openings and valve slides adapted to close certain of the openings independently of the valves; means for actuating the valve slides including a gear, a pinion meshing with the gear, a connecting rod eccentrically connected to the pinion, a shaft mechanically connected to the connecting rod and to the valve slides, pins fixed in the gear, a plunger head adapted to engage the pins and cause the gear to make a partial revolution, and a plunger hinged to the plunger head. 110
10. In an accordion having a piano keyboard, a body part, wind cells in the body part, and valves for closing the wind cells; keys on the keyboard connected to the valves and hinged to the body part at a point substantially beyond the plane of the valves. 115
11. In an accordion having a piano keyboard, a body part, a wind chamber in the body part, wind cells in the wind chamber having an air passage in the end of each, and valves for closing the air passages; a partition separating a key chamber from the wind chamber and having its outer edge in the 120
12. In an accordion having a piano keyboard, a body part, a wind chamber in the body part, wind cells in the wind chamber having an air passage in the end of each, and valves for closing the air passages; a partition separating a key chamber from the wind chamber and having its outer edge in the 125
13. In an accordion having a piano keyboard, a body part, a wind chamber in the body part, wind cells in the wind chamber having an air passage in the end of each, and valves for closing the air passages; a partition separating a key chamber from the wind chamber and having its outer edge in the 130

plane of the air passages, keys on the keyboard connected to the valves and extending into the key chamber, and means for hinging the keys near the inner end of the key chamber.

12. In an accordion having a piano keyboard, a body part, wind cells in the body part, and valves for closing the wind cells, means for opening and closing the valves in-

cluding keys mounted in the keyboard and 10 extending through the plane of the valves and hinged in the body part at a point substantially beyond the plane of the valves, and rods secured to the valves and to the keys intermediate their ends. 15

In testimony whereof I have signed my name to this specification.

FRANK NARDONE.
